(57) **CLAIM**

The ornamental design for a total air temperature probe, as shown and described.

DESCRIPTION

FIG. 1 is a perspective view as seen from the front, side and top of a second embodiment of a total air temperature probe of the present invention;

FIG. 2 is a top plan view of the total air temperature probe of FIG. 1;

FIG. 3 is a bottom plan view of the total air temperature probe of FIG. 1;

FIG. 4 is a front elevational view of the total air temperature probe of FIG. 1;

FIG. 5 is a rear elevational view of the total air temperature probe of FIG. 1;

FIG. 6 is a left side view of the total air temperature probe of FIG. 1; and,

FIG. 7 is a right side view of the total air temperature probe of FIG. 1.

The broken line showing of elements of the total air temperature probe are included for the purpose of illustrating non-claimed subject matter and forms no part of the claimed design.
